UNITED STATES PATENT OFFICE

156,620

REFRIGERATOR TRAY FOR EGGS OR THE LIKE

Hollie C. Gulley, Los Angeles, Calif.

Application December 26, 1947, Serial No. 143,356

Term of patent 3½ years

(Cl. D67—3)

To all whom it may concern:

Be it known that I, Hollie C. Gulley, a citizen of the United States, residing in Los Angeles, in the county of Los Angeles and State of California, have invented a new, original, and ornamental Design for a Refrigerator Tray for Eggs or the like, of which the following is a specification, reference being had to the following drawing, forming part thereof.

Fig. 1 is a top plan view, in partly open position, of a refrigerator tray for eggs or the like, showing my new design;

Fig. 2 is a side elevational view thereof;

Fig. 3 is a front elevational view thereof on a slightly larger scale.

Fig. 4 is a cross-sectional view as taken on the line 4—4 of Fig. 2, and looking in the direction of the arrows.

The dominant features of my design are shown in full lines.

I claim:

The ornamental design for a refrigerator tray for eggs or the like, substantially as shown and described.

HOLLIE C. GULLEY.
